BICAPSULAR GRIP FOR PIVOTED SURGICAL INSTRUMENTS

Pedro D. Curutchet, Loheria, Argentina

Application January 26, 1953; Serial No. 333,091

7. Claims. (Cl. 128—321)

1

This invention relates to a bicapsular grip for pivoted surgical instruments and more particularly it refers to a bicapsular needle holder. The expression "bicapsular" is used to indicate that the instrument comprises two capsular members for housing the thumb's ball and the forefinger's ball and preferably also the tips of an operator or surgeon, and which capsular members are considered as a main feature of the invention.

In the known instruments of the type herein concerned with, and more particularly in all the instruments having two branches pivotally linked together and actuated and controlled by two ring like members fixed to respective ends of said branches, no care has been taken, up to now, to give said ring like members special shapes and to add further accessories to said branches for the other fingers so that the instrument may be conducted and operated in accordance with the anatomic predisposition of the fingers of the hand.

It is therefore convenient to analyze, in first instance, the main functions of each finger of the hand; thus the thumb is the finger which can carry out the largest movements with regard to the rest of the fingers of the hand, the thumb's ball is a large and sensitive surface. Therefore in scissors and any other type of pivoted two lever or two branch instruments, the thumb should carry out the operation of opening and closing the instrument.

The forefinger is the one which may be called the "conductor" since due to its anatomic constitution, it is the one which easily carries out the direction control of the tip of the instrument.

The middle, finger, and the ring finger have complementary functions to which reference will be made later on.

In the known type of instruments having simply two ring like members, no care is taken of the thumb's ball. This surface which due to its elasticity, sensibility and resistance is biologically destined for controlling pressure, is rendered completely useless in the known type of instrument. What is more in said type of instruments it is important and tortured and it protrudes, half chocked from the ring. The ordinary bidigital grips, specially for needle holders and similar instruments are subjected to an obvious fault, in none of them the forefinger has a definite position and it is limited, in the handling of the tool to a secondary role. Only, the thumb and the middle finger or the ring finger have the privilege of occupying the ring like members.

This fault probably is due to the fact that all

said instruments are based on the ordinary scissors. A good number of surgical instruments and especially the needle holders must perform besides the operation of opening and closing the instrument, further motions, such as rotary, circular and lateral motions. This kind of movement requires the specific participation of the forefinger.

In the instrument according to the present invention, the forefinger is located between the ring like member and the pivot of the instrument by means of a capsular member or housing in which the forefinger's ball and tip is located.

On the other branch of the needle holder of the present invention, a ring like member of special anatomic size and shape is provided for the thumb which ring like member is integral with a capsular member outwardly directed for enlarging the contact surface for the thumb's ball. In the preferred embodiment said capsular member is provided with a scale shape plate for the side of the thumb.

The main object of this capsular member is to prevent the ring like member from slipping towards the thumb's root during the operation of the instrument.

In the known instrument no means are provided to avoid this drawback and if such a slippage occurs, the instrument is deviated and the grip loses firmness and then the fingers are no longer capable of properly retaining and controlling the instrument.

Bearing in mind all the drawbacks as above explained, a new bicapsular grip for surgical instruments, such as needle holders and the like has been conceived, comprising a first branch and a second branch pivotally linked together by a pivot, each branch having a free end portion on the same side of said pivot, a first ring like member integral with said free end portion of said first branch and a second ring like member integral with said free end portion of said second branch, a first capsular member having a first cavity and an outer wall, said first capsular member being integral with said first ring like member for housing the thumb's ball and tip of an operator in said first cavity, said outer wall being directed towards said second ring like member, a second capsular member having a second cavity for housing at least the forefinger's ball of said operator, said second capsular member being fixed to said second branch between said second ring like member and said pivot and said second cavity being directed towards said pivot.

From the foregoing it can be understood that

it is an object of the invention to provide a new bicapsular instrument and more particularly a bicapsular needle holder by means of which it is possible to increase considerably the tactile sensitiveness and "conductibility" of such an instrument.

Another object is to supply a needle holder provided with special means for gripping the instrument, which means designate the proper anatomic role to at least four fingers of the surgeon's hand.

Another object is to provide a needle holder which enables a firm and nimble hold of the instrument.

Still another object is to provide a needle holder which engages more fingers than the two ring needle holders, without making the handle of the instrument more complicated.

Another object is to provide a bicapsular needle holder, the capsules of which have the indispensable length so that the ring like member will not exert any substantial pressure on the fingers.

Another object is to provide a capsular member for the forefinger, so that the latter is conveniently raised whereby the pressure of the ring like member for the thumb does not become uncomfortable over the thumb's dorsal surface.

A still further object is to provide the capsular members with an internal striated surface imitating the capillary grooves by means of fine flutings which benefit the retention of the instrument.

A still further object is to provide an arcuate lever for the middle finger located between the ring like member for the ring finger and the capsular member for the forefinger.

These and further objects and advantages of the invention will become apparent in the course of the following description. In order that the invention may be more clearly understood and readily carried out, a preferred embodiment thereof has been illustrated in the accompanying drawings, by way of example.

In the drawings:

Figure 1 is a perspective view of a bicapsular grip applied to a needle holder.

Figure 2 is the same needle holder as shown in Figure 1 but illustrating the position of the surgeon's hand when gripping the latter.

Figure 3 is a plan view of the needle holder of Figure 1.

Figure 4 is a detail of the capsular member integral with the ring like member, for the thumb.

Figure 5 is a detail in lateral elevation of the capsular member for the forefinger.

Although reference is specially made to a "needleholder" it is to be understood that the bicapsular grip may be applied to other similar surgical instruments and the scope of this invention has to be interpreted along these lines.

It may be appreciated from the accompanying drawings, that the bicapsular needle holder 1 comprises a first branch 2 and a second branch 3, pivotally linked together by means of pivot 4 or the like, each branch 2 and 3 having a free end portion 2' and 3', respectively.

The other end of said branches 2 and 3 constitute the needle holder jaws 5 and 6, which are of the known type and therefore will not be described.

The free end portion 2' is integral with a first ring like member 7, which ring like member 7 is bevelled so that the inner surface 7' thereof will enter throughout substantially its entire

length with the thumb's surface without exerting a pressure thereon.

For convenience of describing said ring like member the latter is divided into an outer portion 7a and an inner portion 7b, by axis A. The inner portion 7b is integral with a first capsular member 8, the concavity of which is directed towards the outer portion 7a. Said first capsular member 8 has an outer wall 8' (see Figure 2) directed towards a second ring like member 9 integral with the free end portion 3', as will be later explained.

The inner surface 8'' of the first capsular member 8 reproduces exactly the anatomy of the thumb's ball and it even imitates its capillary grooves by means of fine flutings 10 which benefits the retention of the instrument. A scale shape plate 11, the concavity of which is a continuation of the concavity of the first capsular member 8, is integral with said first ring like member 7 and adjacent to the free end portion 2' and so located that the axis A is approximately an axis of symmetry therefor. Said scale shape plate 11 butts against the corresponding lateral portion of the thumb and thereby decreases the pressure of the ring's top edge 1c and distributes said pressure in a more uniform manner, whereby the tactile sensitivity is considerably increased. The lower portion of the first capsular member 8 is slightly curved, as may be best seen in Figure 3, so that the tip of the thumb butts thereagainst, whereby slippage of the ring like member 7 towards the root of the thumb is avoided.

The second capsular member 9 is also bevelled but in opposite direction as said first capsular member 7 as may be appreciated from axis B and C, respectively, so that also this second ring like member 9 has its inner surface 9' so orientated that it enters throughout its substantially full length in contact with the ring finger, as best seen in Figure 2, wherefrom it is also possible to understand that the instrument is so gripped by the hand that it constitutes a prolongation thereof, or in other words it is substantially parallel to the forearm of the surgeon.

A second capsular member 12 (see also Figure 5) is fixed to said second branch 3, by means of a rib 13. The cavity of said second capsular member 12 is directed towards the pivot 4 and the capsular member is so shaped that said cavity is the negative of the forefinger's tip, ball and part of the middle phalanx, and since the forefinger is usually slightly bent the top portion 12' of said second capsular member 12 is slightly bent backwards towards said free end 3'. The inner surface 12'' of said second capsular member 12 is also provided with fine flutings which benefit the retention of the instrument.

Finally the second branch 3, in the preferred embodiment, is also provided with an arcuate lever 14 the concavity of which is directed towards said second capsular member and which arcuate lever is projecting from said second branch 3 in substantially the same plane as said second ring like member 9.

As may be best seen in Figure 2 the first and second ring like members 7 and 9 as well as the arcuate lever 14 project laterally from the respective branches 2 and 3 so that the thumb, the middle finger and the ring finger will hold the instrument from the outside, whilst the second capsular member 12 is so located that the forefinger will be located on the top of the in-

strument and thereby control the direction of the instrument.

I claim:

1. A bicapsular grip for surgical instruments such as needle holders, pinzers and the like, comprising a first branch and a second branch pivotally linked together by a pivot, each branch having a free end portion on the same side of said pivot, a first ring like member integral with said free end portion of said first branch and a second ring like member integral with said free end portion of said second branch, a first capsular member having a first cavity and an outer wall, said first capsular member being integral with said first ring like member for housing the thumb's ball and tip of an operator in said first cavity, said outer wall being directed towards said second ring like member, a second capsular member having a second cavity for housing at least the forefinger's ball of said operator; said second capsular member being fixed to said second branch between said second ring like member and said pivot and said second cavity being directed towards said pivot.

2. A bicapsular needle holder comprising a first branch and a second branch, a pivot pivotally linking said first and second branches, a first needle holder jaw and a second needle holder jaw integral with said first and second branches, respectively, and located at one side of said pivot, said first branch having a first free end portion opposite said first jaw and at the other side of said pivot, said second branch having a second free end portion opposite said second jaw and also at the other side of said pivot, a first ring like member integral with said first free end portion and a second ring like member integral with said second free end portion, a first capsular member having a first cavity and an outer wall, said first capsular member being integral with said first ring like member for housing the thumb's ball of an operator in said cavity, said outer wall being directed towards said second ring like member, a second capsular member for housing at least the forefinger's ball, said second capsular member being fixed to said second branch between said second ring like member and said pivot and said second cavity being directed towards said pivot.

3. A bicapsular grip for surgical instruments such as needle holders, pinzers and the like, comprising a first branch and a second branch pivotally linked together by a pivot, each branch having a free end portion on the same side of said pivot, a first ring like member integral with said free end portion of said first branch and a second ring like member integral with said free end portion of said second branch, a first capsular member having a first cavity and an outer wall, said first capsular member being integral with said first ring like member for housing the thumb's ball of a surgeon in said first cavity, said outer wall being directed towards said second ring like member, a second capsular member having a second cavity for housing at least the forefinger's ball of said surgeon, said second capsular member being integral with said second branch between said second ring like member and said pivot, said second cavity being directed towards said pivot, an arcuate lever for the middle finger of said surgeon integral with said second branch and located between said second capsular member and said second ring like member.

4. A bicapsular grip for surgical instruments

such as needle holders, pinzers and the like, comprising a first branch and a second branch pivotally linked together by a pivot, each branch having a free end portion on the same side of said pivot, a first bevelled ring like member integral with said free end portion of said first branch and a second bevelled ring like member integral with said free end portion of said second branch, a first capsular member having a first cavity and an outer wall, said first capsular member being integral with said first ring like member for housing the thumb's ball of a surgeon in said first cavity, said outer wall being directed towards said second ring like member, a second capsular member having a second cavity for housing at least the forefinger's ball of said surgeon, said second capsular member being integral with said second branch between said second ring like member and said pivot, said second cavity being directed towards said pivot, an arcuate lever for the middle finger of said surgeon integral with said second branch and located between said second capsular member and said second ring like member, said first ring like member, said second ring like member and said arcuate lever projecting laterally out of the branches, said second capsular member projecting perpendicularly out of said second branch with regard to said second ring like member, the axes of said first and second ring like members being directed in opposite directions.

5. A bicapsular grip for surgical instruments such as needle holders, pinzers and the like, comprising a first branch and a second branch pivotally linked together by a pivot, each branch having a free end portion on the same side of said pivot, a first ring like member integral with said free end portion of said first branch and a second ring like member integral with said free end portion of said second branch, said first ring like member comprising a top edge, an outer portion and an inner portion a first capsular member having a first cavity and an outer wall, said first capsular member being integral with said inner portion of said first ring like member for housing the thumb's ball of a surgeon in said first cavity, said outer wall being directed towards said second ring like member, a second capsular member having a second cavity for housing at least the forefinger's ball of said surgeon, said second capsular member being integral with said second branch between said second ring like member and said pivot, said second cavity being directed towards said pivot, an arcuate lever for the middle finger of said surgeon integral with said second branch and located between said second capsular member and said second ring like member, a scale shape plate integral with said top edge of said first ring like member and capable of contacting the anterior lateral surface of the thumb of the surgeon.

6. A bicapsular grip for surgical instruments such as needle holders, pinzers and the like, comprising a first branch and a second branch pivotally linked together by a pivot, each branch having a free end portion on the same side of said pivot, a first ring like member integral with said free end portion of said first branch and a second ring like member integral with said free end portion of said second branch, a first capsular member having a first cavity and an outer wall, said first capsular member being integral with said first ring like member for housing the thumb's ball of a surgeon in said first cavity, said outer wall being directed towards said second

75 said outer wall being directed towards said second

ring like member; a second capsular member having a second cavity for housing at least the forefinger's ball of said surgeon, said second capsular member being integral with said second branch between said second ring like member and said pivot, said second cavity being directed towards said pivot, an arcuate lever for the middle finger of said surgeon integral with said second branch and located between said second capsular member and said second ring like member, said first and second capsular members each comprising an inner surface provided with fine flutings imitating the capillary grooves.

7. A bicapsular grip for surgical instruments such as needle holders, pinzers and the like, comprising a first branch and a second branch pivotally linked together by a pivot, each branch having a free end portion on the same side of said pivot, a first ring like member integral with said free end portion of said first branch and a second ring like member integral with said free end portion of said second branch, a first capsular member having a first cavity and an outer wall,

said first capsular member being integral with said first ring like member for housing the thumb's ball of a surgeon in said first cavity, said outer wall being directed towards said second ring like member, a second capsular member having a second cavity for housing at least the forefinger's ball of said surgeon, said second capsular member having a rib integral with said second branch between said second ring like member and said pivot, said second cavity being directed towards said pivot, said second capsular member is so shaped that said second cavity is the negative of the forefinger's tip, ball and part of the middle phalanx, said second capsular member having a top portion slightly bent towards said second free end portion, an arcuate lever for the middle finger of said surgeon integral with said second branch and located between said second capsular member and said second ring like member.
